PHASE SPLITTING COUPLING FOR COAXIAL
TRANSMISSION LINESRene A. Braden, Princeton, N. J., assignor to
Radio Corporation of America, a corporation of
Delaware

Application September 27, 1946, Serial No. 699,682

9 Claims. (Cl. 250—33)

1

This invention relates generally to wave transmission lines and more particularly to coupling networks for connecting coaxial transmission lines to certain types of load devices such, for example, as dipole antennas and the like.

Heretofore, various means have been employed for coupling coaxial transmission lines to oppositely phased load devices wherein the required phase reversal currents have been derived by separate half-wave coaxial line arms interposed between the main transmission line and one of the load devices. One of the principal disadvantages of such auxiliary phasing devices is that high frequency currents are carried by the external line conductors in the vicinity of the load, thus providing undesirable radiation fields. Also such systems are inherently cumbersome and unsymmetrical in appearance.

The instant invention contemplates the use of a third coaxial tubular conductor interposed between the inner and outer coaxial conductors of the coaxial transmission line in the vicinity of one of the loads to be coupled thereto. The outer coaxial line conductor is enlarged in the vicinity of a complementarily enlarged portion of the intermediate conductor to provide therebetween a wave path which is an odd multiple of one-half wavelength at the operating frequency longer than the wave path between the inner and intermediate coaxial conductors. The dipoles are connected respectively to the inner and intermediate conductors, and thus are energized by high frequency currents of opposite phase. In effect, the high frequency waves propagated along the transmission line are divided into two portions which are effectively in series in the region occupied by the intermediate coaxial conductor. Wave reflections on the line from the intermediate conductor may be minimized by tapering the end thereof facing toward the wave generator, such as by terminating the generator end thereof at an angle to the electric field axis. If desired, a quarter wave stub support may be provided at the end of the three-conductor portion of the line remote from the generator.

Among the objects of the invention are to provide an improved method of and means for transforming unbalanced currents in a coaxial transmission line to balanced currents for application to a dipole antenna or similar load devices. Another object is to provide an improved coaxial line transformer for coupling a conventional two-conductor coaxial line to oppositely-phased loads such as a dipole antenna or the like. Another object is to provide an improved coaxial line network

2

for coupling a two-conductor coaxial line to a dipole antenna, and for supporting the dipole elements with respect to the coaxial line conductors. A further object is to provide an improved coupling network for coupling a coaxial transmission line to oppositely-phased load devices such as dipole antennas, or the like, wherein substantially no extraneous radiation field is provided by the outer coaxial line conductor in the vicinity of the balanced load.

The invention will be described in greater detail by reference to the accompanying drawing of which Figure 1 thereof is a cross-sectional, elevational view of a preferred embodiment of the invention as applied to energization of a dipole antenna; and Figure 2 is an enlarged fragmentary cross-sectional view of the right hand portion of the device of Fig. 1. Similar reference characters are applied to similar elements throughout the drawing.

Referring to Figure 1 of the drawing, a coaxial transmission line comprising an inner conductor 1 and a concentric outer conductor 3 is connected to a source, not shown, of high frequency energy. An intermediate tubular conductor 5 having a tapered end 7 facing toward the source of wave energy is interposed between the coaxial inner and outer transmission line conductors 1, 3 in the immediate vicinity of a dipole antenna or other oppositely-phased load devices to be coupled to the line. The intermediate conductor 5 includes an outwardly projecting portion 9, and the outer conductor 3 also includes a complementarily projecting portion 11 providing desired spacing of the intermediate and outer conductors in the region of the projecting portion 9 of the intermediate conductor. The inner surface 13 of the tubular intermediate conductor 5 is cylindrical and concentric with the inner line conductor 1. Thus the wave propagation path between the outer and intermediate conductors 3, 5, respectively, is proportioned to be an odd multiple of one-half wavelength

$$45 \quad \left(\frac{(2n+1)}{2} \lambda + c \right)$$

in the line at the operating frequency longer than the wave propagation path $(n\lambda + c)$ between the intermediate and inner line conductors 5, 1, respectively, in the vicinity of the load. The surge impedance of the concentric line section comprising the outer and intermediate conductors 3, 5 may be made uniform throughout the length of the line section by maintaining constant the ratio of the inner diameter of the outer conductor to the outer diameter of the intermediate conductor.

A dipole antenna comprising a pair of dipole stubs 15, 17, is connected to the inner and intermediate line conductors 1, 5 through suitable apertures 19 in the outer coaxial conductor 3. For example, the first dipole 15 is connected to the inner coaxial conductor 1 and projects outwardly through an aperture 21 in the intermediate conductor 5 and a coincidental one of the apertures 19 in the outer conductor 3. In order properly to guide the waves A propagated between the inner and intermediate conductors through the field B between the intermediate and outer conductors, the intermediate conductor includes an outwardly projecting sleeve 23 having an annular end ring 25. The sleeve 23 and ring 25 effectively isolate the dipole stub 15 from the wave energy B propagated between the intermediate and outer conductors. Similarly, the other dipole stub 17 passes through the other aperture 19 in the outer coaxial conductor 3 and is connected to the intermediate conductor 7, at a point diametrically opposite to the point of connection of the dipole stub 15.

In order to support the dipoles and the three coaxial conductors 1, 3, 5 in proper relative position, the ends of the three coaxial conductors may be connected together by an annular conductive plug 27 at a point any odd number of quarter wavelengths

$$\left(\frac{(3n+1)}{4} \lambda \right)$$

in the line at the operating frequency from the dipole antenna stubs 15, 17. It should be understood that any other type of oppositely-phased loads, other than the dipole antenna described heretofore, may be connected in a similar manner to the inner and intermediate conductors.

The operation of the system may be more clearly understood by reference to Figure 2 of the drawing wherein the wave energy A propagated between the inner and intermediate conductors 1, 5 is indicated by the dash line arrows 29, and the oppositely phased wave energy propagated between the intermediate and outer conductors 5, 3 is indicated by the solid line arrows 31. The waves A are guided out by the inner end of the dipole stub 15 through the space between the dipole stub and the coaxial sleeve 23 and are launched into space as an electromagnetic wave radiation. The wave A therefore may be considered as existing in the space between the inner conductor 1 and the inside surface of the intermediate conductor 5 and the inside surface of the sleeve 23.

Likewise, the wave B, which is delayed one-half period from the wave A, may be considered as traveling in the space between the outside surface of the intermediate conductor 5 and the inside surface of the outer conductor 3. The wave B, therefore, travels out to the end of the second dipole stub 17 and is radiated into space as a second electromagnetic wave which is oppositely-phase with respect to the waves radiated by the first dipole stub 15.

It will be apparent that currents flow on the outer surface of the outer conductor 3 only in the vicinity of the second dipole stub 17 and possibly within a very limited region between the outer conductor 3 and the under surface of the annular ring 25. Otherwise all of the currents in the line flowing as a result of propagation of the waves B travel on the inner surface of the outer conductor 3 and the outer surface of the intermediate conductor 5. Likewise the currents in the line re-

sulting from propagation of the wave energy A travel only on the inner surface of the intermediate conductor 5 and the outer surface of the center conductor 1. The sleeve 23 and annular ring 25 effectively shield the first dipole stub 15 from currents traveling on the outer conductor 3.

Thus the invention disclosed comprises an improved coaxial line coupling network for coupling a two conductor concentric line to oppositely-phased load devices, such as antenna dipoles, wherein the coupling structure is completely enclosed within a shielding portion of the outer transmission line conductor, and support for the load and the ends of the line conductors is provided by a quarter wave coaxial line stub. Oppositely phased currents for the antenna or loads are provided by the insertion of an intermediate coaxial conductor between the inner and outer coaxial line conductors wherein projecting portions of the intermediate and outer conductors provide the required phase delay with respect to the directly propagated wave energy. The oppositely phased waves in the vicinity of the antenna are segregated by a radially extending sleeve surrounding and coaxial with one of the dipole stubs in the region where it projects through the space between the intermediate and outer line conductors.

I claim as my invention:

1. A network for coupling a transmission line having coaxial inner and outer conductors to oppositely phased load devices including a portion of said outer line conductor having a larger diameter than the remainder thereof, a third coaxial tubular conductor interposed between said inner and outer conductors, said third conductor also having a portion having a larger diameter than the remainder thereof, said larger diameter portions of said outer and third conductors being aligned to provide with said inner and outer conductors two concentric lines differing in length by substantially an odd number of one-half wavelengths in the line at the operating frequency, and means for connecting said load devices respectively to said inner and third conductors.

2. Apparatus according to claim 1 wherein the end of said third conductor remote from said loads is tapered to reduce wave reflections in said transmission line.

3. A network for coupling a transmission line having coaxial inner and outer conductors to a pair of dipole antenna stubs including a portion of said outer line conductor having a larger diameter than the remainder thereof, a third coaxial tubular conductor interposed between said inner and outer conductors, said third conductor also having a portion having a larger diameter than the remainder thereof, said larger diameter portions of said outer and third conductors being aligned to provide with said inner and outer conductors two concentric lines having substantially uniform surge impedances along the lengths thereof, said line lengths differing by substantially an odd number of one-half wavelengths in the line at the operating frequency, and means for connecting said dipole antenna between said inner and third conductors.

4. A network for coupling a transmission line having coaxial inner and outer conductors to oppositely phased load devices including a portion of said outer line conductor having a larger diameter than the remainder thereof, a third coaxial tubular conductors interposed between said inner and outer conductors, said third conductor

also having a portion having a larger diameter than the remainder thereof, said larger diameter portions of said outer and third conductors being aligned to provide with said inner and outer conductors two concentric lines having substantially uniform spacing along the lengths thereof, said line lengths differing by substantially an odd number of one-half wavelengths in the line at the operating frequency, and means for connecting said load devices to said inner and third conductors.

5. A network for coupling a transmission line having coaxial inner and outer conductors to a dipole antenna including a portion of said outer line conductor having a gradually increasing larger diameter than the remainder thereof, a third coaxial tubular conductor interposed between said inner and outer conductors, said third conductor also having a portion having a larger diameter than the remainder thereof, said larger diameter portions of said outer and third conductors being aligned to provide with said inner and outer conductors two concentric lines differing in length by substantially an odd number of one-half wavelengths in the line at the operating frequency, means for connecting said antenna dipoles to said inner and third conductors at points substantially an odd number of quarter wavelengths from the ends of said conductors, and means connecting together and supporting said ends of all of said conductors.

6. A network for coupling a transmission line having coaxial inner and outer conductors to a pair of dipoles including a portion of said outer line conductor having a larger diameter than the remainder thereof, a third coaxial tubular conductor interposed between said inner and outer conductors, said third conductor also having a portion having a larger diameter than the remainder thereof, said larger diameter portions of said outer and third conductors being aligned to provide with said inner and outer conductors two concentric lines differing in length by substantially an odd number of one-half wavelengths in the line at the operating frequency, means for separately connecting said dipoles to said inner and third conductors, and means shielding one of said dipoles from the field in said line energizing the other of said dipoles, said dipoles being energized in opposite phase.

7. A network according to claim 6 wherein the end of said third conductor remote from said load is tapered to reduce wave reflections in said transmission line, said dipoles are connected to said conductors at points an odd number of quarter wavelengths from the ends thereof remote from said tapered portion, and means for connecting together and supporting said ends of all of said conductors remote from said tapered portion and said dipoles.

8. A network for coupling a source of high frequency energy through a transmission line having coaxial inner and outer conductors to a pair of dipoles including a portion of said outer line conductor having a larger diameter than the remainder thereof, an intermediate tubular conductor interposed between said inner and outer conductors, said intermediate conductor also having a portion having a larger diameter than the remainder thereof, said larger diameter portions of said outer and intermediate conductors being aligned to provide with said inner and outer conductors two concentric lines differing in length by substantially an odd number of one-half wavelengths in the line at the operating frequency, means for connecting said dipoles respectively to said inner and intermediate conductors at points an odd number of quarter wavelengths from the ends thereof remote from said source, means conductively terminating and supporting the ends of all of said conductors remote from said source whereby said load is effectively balanced with respect to said outer line conductor, and means comprising a cylindrical sleeve and an annular ring coaxial with one of said dipoles and connected to said intermediate conductor for shielding said last-mentioned dipole from wave energy propagated between said intermediate and outer line conductors.
- 10 9. A network for coupling a transmission line having coaxial inner and outer conductors to oppositely phased load devices, including a portion of one of said coaxial line conductors having a different diameter than the remainder thereof, a third coaxial tubular conductor interposed between said inner and outer conductors, said third conductor also having a portion having a different diameter than the remainder thereof, said different diameter portions of said coaxial and third conductors being complementarily aligned to provide with said inner and outer conductors two concentric lines differing in length by substantially an odd number of one-half wavelengths in the line at the operating frequency and means for connecting said load devices respectively to one of said coaxial conductors and said third conductor.
